LOUDSPEAKER ARRANGEMENT

Alfred Wiessner, Berlin, Germany, assignor to C. Lorenz Aktiengesellschaft, Berlin-Tempelhof, Germany, a company

Application December 17, 1937, Serial No. 180,338
In Germany December 22, 1936

5 Claims. (Cl. 179—1)

In the operation of loudspeakers it is in certain cases desirable to have their circuits closed from a remote station, thus dispensing with a local attendant. Such is the case, for instance, if the loudspeakers are to operate at a desired time only, requiring them to be actuated instantly.

In accordance with the invention a sound emitting apparatus of the loudspeaker type shall be operable from a remote transmitting station and by means of predetermined signals, the communications and other signals intended for transmission being conveyed to the sound emitting apparatus with the aid of a carrier frequency. According to a further feature of the invention part of the output energy of this apparatus is used for obtaining a revertive indication and for supervision. It is of advantage here that a single line may be utilized for both feeding such apparatus and permanently supervising the operation thereof.

The invention will be understood from the following description, reference being had to the accompanying drawing which shows a diagram of one embodiment thereof.

1 denotes a sound emitting apparatus which is to be attended to and supervised from a remote station 12. The apparatus 1 here shown by way of example comprises an amplifier and rectifier 2, an output amplifier 3, a loudspeaker 4 or a number thereof, a high pass filter 5, and a low pass filter 6. Station 12 is a transmitting station which comprises a high frequency transmitting device 7, a high pass filter 8, a low pass filter 9 and a supervision device 10. The stations 1, 12 are interconnected by a line 11 of any desired or suitable length.

The operation is as follows.

In order to effect a transmission, apparatus 1 is at first rendered ready for operation. For instance, a predetermined signal, such for example as a low frequency current of 50 cycles per second, is impressed upon line 11 from station 12. Such current acts to render the high frequency receiver or rectifier 2 ready for operation, for instance by energizing a tuned relay or the like. In order now to operate the sound emitting apparatus 1 a modulated carrier frequency is conveyed thereto from device 7 over the filters 8, 5. In apparatus 1 this frequency causes the final stage, for instance, of the sound amplifier to be switched in or acts to close the circuit of the loudspeaker 4 itself. Thereupon the transmission of communications, effected by means of the carrier frequency modulated by device 7, takes place. This

frequency is in a well-known manner conveyed over the high pass filter 5 to device 2 and amplified by device 3, being then emitted by loudspeaker 4. Part of the voice frequency is derived at a point in advance of the loudspeaker and is carried back to line 11 over low pass filter 6. At station 12 the voice frequency is taken from line 11 over filter 9 and is indicated by supervision device 10 acoustically or optically.

To employ a carrier frequency for feeding the loudspeaker apparatus involves the great advantage that the speech on its passage along line 11 is not liable to distortion. By having the voice frequency indicated at station 12 the advantage is obtained that here the voice frequency amplitude of the loudspeaker can be ascertained by direct measurement, the attenuation which this low frequency energy undergoes on its passage along line 11 being small as compared with that of the high frequency energy. If the high frequency energy on its passage along line 11 is too much attenuated, or if the intensity of the emitted sound is found to be too low, then station 12 will be able in a simple manner to obtain a readjustment by increasing the transmitting amplitude.

Instead of the revertive indication effected by means of a voice frequency, an indication on a carrier frequency different from the transmitting wave may be provided. For instance, with a transmitting frequency of 50 kilo-Hertz a revertive indication on a frequency of 10 kilo-Hertz may take place, this frequency being modulated with the output energy of the loudspeaker apparatus.

The amplifying means may be cut in by any suitable remote control devices other than those here described. Furthermore, telephone lines may be employed for rendering the loudspeaker apparatus effective. The disconnection of this apparatus is obtained with the same means by which it is switched in.

What is claimed is:

1. Loudspeaker arrangement comprising: a transmitter including means for producing a modulated carrier current and means for producing a control current; a receiver remote from said transmitter and including a sound emitting apparatus, means for demodulating said carrier current, means responsive to said control current and adapted to render said receiver operative; means to convey said carrier current and said control current in one direction from the transmitter to the receiver, and further means for con-

veying a revertive signal in the opposite direction.

- 5 2. A loudspeaker arrangement comprising a sound emitting apparatus, a transmitting station remote therefrom, means in this station for producing a modulated carrier frequency, means in the same station for producing energy adapted to switch-in the sound emitting apparatus, a line interconnecting this apparatus and said station and adapted to convey the said switch-in energy and carrier frequency to the sound emitting apparatus, and means for causing energy, adapted to effect a revertive indication, to be conveyed from this apparatus to the transmitting station.
- 10 3. A loudspeaker arrangement comprising a sound emitting apparatus, a transmitting station remote therefrom, means in this station for producing a modulated carrier frequency, means in the same station for producing a voice frequency adapted to switch-in the sound emitting appa-
- 15 20

ratus, a line interconnecting this apparatus and said station and adapted to convey said carrier frequency and voice frequency to the sound emitting apparatus, and means to cause part of such voice frequency to be carried back into the said line, this part being adapted to effect a revertive indication.

4. An arrangement according to claim 2, having means to produce a second carrier frequency as the energy adapted to effect the said revertive indication.

5. An arrangement according to claim 1, having a high frequency portion adapted to be cut in by low frequency energy and in remote control fashion, and a low frequency portion adapted in remote control fashion to be cut in by a carrier frequency modulated with a predetermined frequency.
